CLAIM

The ornamental design for a set of panels for a carrying accessory as shown and described.

DESCRIPTION

FIG. 1 is a front perspective view of a set of panels for a carrying accessory according to my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines in the figures, including panels shown in broken lines in the left side, right side, top, and bottom views, illustrate features of a carrying accessory that form no part of the claimed design.

1 Claim, 7 Drawing Sheets
